UNITED STATES PATENT OFFICE

2,570,610

GAS BLAST CIRCUIT BREAKER WITH TRAP
FOR PRODUCTS OF ARCINGPhilip L. Taylor, Abington, Mass., assignor to
Allis-Chalmers Manufacturing Company, Milwaukee, Wis., a corporation of Delaware

Application August 23, 1947, Serial No. 770,296

5 Claims. (Cl. 200—148)

1

This invention relates in general to improvements in circuit breakers of the gas blast type and more particularly to means for reducing the contamination of the gas blast, particularly the contamination produced by material removed from the contacts by the action of the arc.

In a circuit breaker, arc initiation occurring upon parting of the contacts is an explosion-like phenomenon. Jets of melted and vaporized metal and other products of arcing are ejected from the gap formed between the separated contacts. The products of arcing form a high pressure zone adjacent the separated contacts, and this high pressure zone tends to stall the flow of arc extinguishing gas under pressure which, in circuit breakers of the gas blast type, is being caused to rush toward the contact gap and the zone wherein the arc is extended and extinguished.

About the time of current zero, the back pressure decreases, thus reducing the resistance which the arc extinguishing blast must overcome to de-contaminate the arcing zone. During the time that that blast has been impeded by the back pressure of products of arcing, the gas under pressure may be contaminated by products of arcing, which diffuse or are projected in all directions, including upstream and downstream directions. It may thus happen that the contact gap and the arc extinguishing zone are being supplied with a blast of partly contaminated or ionized gas rather than a blast of clean gas having a high dielectric strength.

It is therefore an object of the present invention to provide a circuit breaker of the gas blast type in which a large portion of the products of arcing is promptly removed from the gas blast.

Another object of the present invention is to provide a circuit breaker of the gas blast type in which products of arcing are directed toward a zone in which such products are trapped out of the main gas flow.

Another object of the present invention is to provide a circuit breaker of the gas blast type in which products of arcing are condensed and trapped by eddies produced in the gas flow by suitable configuration of the gas conduit.

Another object of the present invention is to provide a circuit breaker of the gas blast type in which products of arcing are temporarily stored outside of the blast serving to extinguish the arc.

Objects and advantages other than those above set forth will be apparent from the following description when read in connection with the accompanying drawing, in which:

Fig. 1 is a view partly in elevation and partly in vertical cross section through one embodiment

2

of the invention in which material removed from the contacts is directed into a zone of increased cross section of the blast forming a pocket;

Fig. 2 is a partial view in vertical cross section of a modified embodiment of the invention in which products of the arc are directed toward a surface guiding the arc products toward a pocket forming an eddy zone in the gas stream; and

Fig. 3 is a partial view in vertical cross section of a modified embodiment of the invention in which the products of arcing are directed into a pocket substantially abstracted from the gas stream.

Referring more particularly to the drawing by characters of reference, numerals 6, 7 designate a pair of insulators adapted to support the contacts 8, 9 of a circuit breaker of the gas blast type. Contact 8 is a fixed contact having the arcing portion thereof disposed within a hollow insulating member 11 defining an elongated passage or contact chamber 12. Suitable arc extinguishing gas such as air under suitable pressure obtained from a reservoir, not shown, may be caused to flow through chamber 12 to extinguish the arc drawn between contacts 8, 9 upon separation thereof. Chamber 12 is built with a cross section of suitable size and configuration to cause the gas blast to reach the desired velocity, which preferably approaches the velocity of sound, as is well known.

Contact 9 is pivotally supported on insulator 7 and may be moved in and out of abutting engagement with contact 8 by means of a suitable motor, not shown, through a mechanism including a connecting rod 13. Leakage of gas about contact 9 through the wall of member 11 may be reduced by the provision of labyrinth passages 14.

The outlet of chamber 12 communicates with an arcing chamber 15 preferably defined by a tubular member 16 at least partly of insulating material. An insulating barrier 17, which may be of gas evolving material, is disposed within chamber 15 to cause the path of the blast to present two enlarged zones 18, 19 separated by a constricted zone 20. The cooperating surfaces of contacts 8, 9 are in general alignment with zone 18.

When current is to be interrupted, contact 9 is moved out of engagement with contact 8. An arc is drawn between the cooperating surfaces of the contacts. The arc causes material of the contacts to be vaporized or otherwise removed with explosive force between the contacts. A large portion of the removed contact material, in the form of incandescent particles, metallic vapors, and clouds of metallic oxides, is guided

by the cooperating surfaces of contacts 8, 9 and is sprayed as indicated by dotted line 10 toward the surface of barrier 17 defining the enlarged zone 18.

The contact material reaching zone 18 is subjected to the deionizing action of the surface of barrier 17 and is partly deposited on the wall of barrier 17 defining zone 18. Some of the contact material remains in suspension in the gas contained in zone 18. As a result of the pocket-like configuration of zone 18, the air flow forms therein an eddy which retains a large portion of the contact material out of the air stream, at least during the time required for finally interrupting the current. Another part of the contact material is carried by the air stream into zone 19, wherein such material is trapped by another eddy formed by the gas stream.

The gas stream is thus stripped to a large extent of contaminating material. After the first passage of the arc current through the value zero, the condition of the gas stream will be unfavorable for the re-establishment of a continuous bridge of ionized gas between contacts 8, 9. Re-establishment of the arc between the contacts will therefore be hindered to a considerable extent by the action of barrier 17.

In the embodiment partly illustrated in Fig. 2, the cooperating surfaces of contacts 8, 9 are in alignment with a surface 21 of barrier 17 situated immediately adjacent the contacts on the downstream side thereof. The products of arcing, ejected along a path indicated by dotted line 30, collect along surface 21, which surface directs the products into zone 18. The latter again forms a pocket within which the collected and partly deionized arc products are trapped to a large extent as in the embodiment illustrated in Fig. 1. Some of the remaining arc products are trapped in the eddy formed in zone 19.

As shown in Fig. 2, the extinguishing action of the gas blast may be assisted by the provision within chamber 15 of a probe 22 connected with one of contacts 8, 9 through a suitable resistor 23.

In the embodiment illustrated in Fig. 3, an insulating barrier 24, which may be of gas evolving material, is disposed entirely within the gas stream. Barrier 24 defines a pocket 25, and the cooperating surfaces of contacts 8, 9 are in alignment with the opening of pocket 25. The arc products are thus sprayed into the pocket, in which the gas blast forms an eddy which retains a large portion of the arc products during the arc interrupting process. Some of the arc products are also carried by the gas blast through a constricted zone 26 defined by the walls of barrier 24 and member 16 and into an enlarged zone 27, in which the gas stream forms a second eddy in which such products of arcing are temporarily retained. The gas stream is thus stripped of a large portion of the contaminating material as in the embodiments illustrated in Figs. 1 and 2.

Although but a few embodiments of the present invention have been illustrated and described, it will be apparent to those skilled in the art that various changes and modifications may be made therein without departing from the spirit of the invention or from the scope of the appended claims. Other species of the invention are disclosed and claimed in U. S. Patent 2,426,250, of Philip L. Taylor, issued August 26, 1947.

I claim:

1. In a gas blast circuit breaker, passage-defining wall means, a pair of relatively movable contacts arranged in the passage defined by said wall

means and adapted to form an arc gap therebetween upon separation thereof, means for establishing a blast of gas through said passage and gap, said passage-defining wall means including means defining a pocket situated downstream of said gap for receiving products of arcing, said pocket-defining means being arranged at the zone of intersection between the jet of products of arcing issuing from said gap and said passage-defining wall means.

5. In a gas blast circuit breaker, means defining a passage, a pair of abutting relatively movable contacts arranged to engage along a predetermined plane and adapted to form an arc gap therebetween upon separation thereof, means for establishing a blast of gas through said passage and gap, and pocket defining means in said passage arranged to intersect said plane formed by said contacts for receiving the products of arcing directly from said gap.

15 6. In a gas blast circuit breaker, means defining a passage, a pair of abutting relatively movable contacts arranged in said passage and adapted to form an arc gap therebetween upon separation thereof, said contacts engaging each other along a predetermined plane extending at an acute angle to the axis of said passage, means for establishing a blast of gas through said passage and gap, and pocket defining means arranged in said 25 passage to intersect said plane for receiving the products of arcing directly from said gap.

20 7. In a gas blast circuit breaker, means defining a passage, a pair of cooperating relatively movable contacts arranged in said passage and adapted to form an arc gap therebetween upon separation thereof, 35 said contacts engaging each other along a predetermined plane extending at an acute angle to the axis of said passage, means for establishing a blast of gas through said passage and gap, and pocket defining means arranged in said 40 passage to intersect said plane for receiving the products of arcing directly from said gap.

45 8. In a gas blast circuit breaker, means defining a passage, a pair of relatively movable contacts arranged in said passage and adapted to form an arc gap therebetween upon separation thereof, means for establishing a blast of gas through said 50 passage and gap, an insulating surface in close vicinity of said gap arranged generally in the direction of the jet of products of arcing issuing from said gap for guiding said products of arcing in a predetermined direction away from said gap, and insulating pocket means defining an eddy current zone for trapping and retaining in said 55 pocket the products of arcing collected by said surface.

PHILIP L. TAYLOR.
